UNITED STATES PATENT OFFICE

2,412,008

LAST

Louis W. Reinhardt, Brockton, Mass.

Application March 16, 1944, Serial No. 526,727

6 Claims. (Cl. 12—136)

1

My present invention relates to lasts and particularly to that type of last used in the so-called "slip-lasting" of footwear.

In accordance with one method of making footwear, a sole member, serving as an insole, is attached to the upper, a last is then inserted, and the sole structure is then attached to the insole member. In such shoe manufacture, the upper, with its attached sole member, is relatively shapeless and commonly is made without a counter. It is accordingly difficult to avoid stretching the upper when the last is inserted.

Lasts for use in lasting shoes made by this method consist of a fore part and a heel part severed on an inclined plane through the waist of the last by offset saw kerfs from opposite sides and split apart to form discontinuous mutually contacting rearwardly and downwardly inclined faces with the fore part having adjacent its bottom surface a rearwardly disposed ledge or shoulder, formed by the above-mentioned splitting, to serve as a stop for the complementary shoulder left on the back part. The fore part and the heel part are formed with alined pockets or narrow kerfs to accommodate a connecting member by which the last parts are pivotally connected to permit the last parts to be collapsed for insertion into the upper and to have a toggle action when the heel part is pressed down to bring the last faces into contact. All of this is generally old in the prior art.

Such lasts usually included means to interconnect the last parts when the last is expanded in the upper and it is to the provision of a rigid and easily operated connection that my invention is particularly directed.

I accomplish this result in accordance with my present invention by forming the last parts with a bore extending diagonally forwardly from the upper surface of the heel part in advance of the jack socket into the fore part laterally of the longitudinal kerf pocket in which the connecting member is pivotally held as by transverse pins at its opposite end. This bore receives a locking unit in the form of a pair of resilient arms to engage frictionally with the bore with one of the arms formed to establish a shoulder defining a slot for a keeper pin. By this construction, I provide a rigid connection that is easily operated and may be used to pull the last from the upper as the locking unit is retracted to its inoperative position.

In the drawing illustrative of my invention, I have shown a last in accordance with it and suggested a shoe of the "slip-lasted" type.

2

Fig. 1 shows such a shoe longitudinally sectioned to expose a last in accordance with my invention.

Fig. 2 is a longitudinal section of the last without the shoe.

Fig. 3 is a view of the contact face of the fore part.

Fig. 4 is a similar view of the rear part.

Fig. 5 is a side view of the locking member, and

Fig. 6 is a view of the handling hook for unlocking the last parts and removing the last from the shoe.

Referring to Fig. 1 of the drawing, I have indicated a shoe upper 10 having a tongue 11 and insole 12. In it, I have indicated the fore part of a divided last at 13 and a rear or back part at 14 as having a usual jack hole or socket. The rear part 14 also has a transverse hole 16 through the heel part just ahead of the jack socket. The fore part 13 and the heel part 14 are formed with rearwardly and downwardly inclined faces 17 and 18, respectively. The forepart 13 adjacent its lower edge is formed with a shoulder 19 adapted to serve as a seat for the complementary shoulder 20 on the heel part 14.

The last parts are formed with alined pockets or slots 21 to receive a link or links 22 pivotally connected to the last parts by pins 23. Any type of connecting means may be used, either unitary or laminated, provided the connecting means work freely in the slots 21 so that the parts have freedom in their slippage and relative movement, and provided that such means substantially fill the slots 21 to hold them alined.

The locking member generally indicated at 24 is an important factor in my present invention as it provides efficient and economical means of splinting the last parts in their extended position. It is preferably made from half-round wire bent to form two arms 25 of substantial length connected by a rounded eye portion 26 adapted to be engaged by the hook 27 and to provide an external stop to prevent the member 24 from being pushed in too far. The eye or loop 26 also serves to resiliently space the opposite flat faces of the arms 25. The end of one arm 25 is bent as at 28 to engage the flat face of the other arm adjacent its end to provide a shoulder.

I form the heel parts 14 with a bore 29 extending forwardly and downwardly from the upper surface of the heel part 14 to register, when the last is in its extended position, with a forwardly and downwardly extending bore 30 in the fore part 13. The bores 29 and 30 are adapted to frictionally receive the locking member 24 and are

spaced laterally of the slots 21. A pin 31 in the heel part 14, extends between the arms 25 of the locking member 24 and is engageable by the shoulder 28 to prevent the locking member 24 from being withdrawn from the heel part 14 and to permit the last to be collapsed and withdrawn from the shoe by pulling on the locking member 24. In this operation the hook 27 may be used to advantage. Occasionally, a last is difficult to remove by pulling on the locking member 24 and it is for that reason that I provide the back part 14 with the transverse bore 16 so that the back part 14 may be directly engaged by the hook 27.

In use, the fore part 13 of the collapsed last is inserted into a shoe and the heel of the rear part 14 is positioned as shown in its dotted line position in Fig. 1. The front of the heel part 14 is then depressed to bring the last into its extended position characterized by the inclined faces 17, 18 and the complementary shoulders 19 and 20 being in mutual contact. The locking member 24 is then pushed forwardly to connect the last parts.

Because of the length of the bores 29 and 30 and because of the length and nature of the locking member 24, my invention provides for a very rigid but easily operated connection and provides effective means to make so-called "slip-lasts" extremely satisfactory in use.

What I therefore claim and desire to secure by Letters Patent is:

1. In a divided last, a fore part and a heel part having inclined faces contactable in a plane secant of the waistline zone of the last, a link connection pivotally connected to each permissive of the relative sliding and swinging of the parts, a bore extending from the upper face of the heel part forwardly and downwardly into the fore part and a locking member slidably in said bore between a position in which it locks the last parts together and a position in which the last parts are unlocked, said member consisting of a pair of resilient arms and a head, the end of one arm being inturned to meet the other arm, and a keeper pin disposed transversely between said spaced arms to limit rearward movement of said member to establish the unlocked position.

2. In a divided last, a fore part and a heel part having inclined shouldered faces contactable in a plane secant of the waistline zone of the last, a link connection pivotally connected to each permissive of the relative sliding and swinging of the parts, a bore extending from the upper face of the last forwardly and downwardly into the fore part, a locking member slidably in said bore and consisting of a pair of half-round arms having their flat faces resiliently held spaced by an intermediate integral loop constituting an exterior head stop, the end of one arm being inturned to meet the flat face of the other and a keeper

pin disposed transversely between said spaced arms permissive of limited sliding movement but constituting an internal longitudinal stop for the said inturned arm end.

3. The last of claim 2, in which the head of the locking member is engageable by a hook and the bore is forwardly of the jack socket, and the last has a transverse bore between the jack socket and the member receiving bore also engageable by the hook.

4. In a divided last, a fore part and a heel part, a link connection pivotally connected to each of said parts to permit said last parts to be positioned relative to each other so that said last may have open and closed positions, a bore extending through the heel part, a bore extending downwardly into the fore part and alining with said first named bore when said last is in its closed position, and a locking member in said first bore slidable into said second bore when said last is in its closed position thereby to establish a locked position for said member, said member having a slot, and a keeper pin carried by said heel part and extending through said slot to limit rearward movement of said locking member to establish its unlocked position.

5. In a divided last, a fore part and a heel part, a link connection pivotally connected to each of said parts to permit said last parts to be positioned relative to each other so that said last may have open and closed positions, a bore extending downwardly through the heel part, a bore extending downwardly into the fore part and alining with said first named bore when said last is in its closed position, and a locking member slidably locked in said first named bore and slideable into said second named bore when said last is in its closed position thereby to lock said last parts, said member comprising a pair of interconnected arms spaced to resiliently engage in said bore.

6. In a divided last, a fore part and a heel part, a link connection pivotally connected to each of said parts to permit said last parts to be positioned relative to each other so that said last may have open and closed positions, a bore extending downwardly through the heel part, a bore extending downwardly into the fore part and alining with said first named bore when said last is in its closed position, a locking member in said first named bore slidable into said second named bore when said last is in its closed position thereby to lock said last parts, said member comprising a pair of interconnected arms spaced to resiliently engage in said bore, and stop means carried by said heel part and engaging with said locking member when said locking member is withdrawn from said second named bore.
